UNITED STATES PATENT OFFICE.

FRIEDRICH HASSENPLUG, OF NEW YORK, N. Y.

WOVEN TRIMMING.

SPECIFICATION forming part of Letters Patent No. 506,365, dated October 10, 1893.

Application filed August 18, 1891. Serial No. 402,993. (Specimens.)

To all whom it may concern:

Be it known that I, FRIEDRICH HASSEN-
PFLUG, a citizen of the United States, residing
at New York city, in the county of New
5 York and State of New York, have invented
certain new and useful Improvements in
Woven Trimmings, of which the following is
a specification.

This invention relates to an improved trim-
ming, in which trams of silk, mohair or other
suitable material are interwoven with the
heading in such a manner that a selvage is
formed at each side of the heading and that
in the facing cut trams and looped or uncut
15 trams of any suitable design are formed,
whereby a very characteristic and highly ornamental
trimming for ladies' garments is obtained; and the invention consists of a trimming
composed of a heading formed of warp-
20 threads and of tram weft-threads which are
interwoven with the warp-threads so as to
form a facing for the heading and a selvage
at each side of the same, the facing being
composed of cut trams and of looped or un-
25 cut trams which are disposed of in the fac-
ing according to a regular design, as will be
fully described hereinafter and finally pointed
out in the claim.

In the accompanying drawings, Figure 1,
30 represents a top-view of my improved trim-
ming. Fig. 2, is a top-view of the same, after
the edges are trimmed and the auxiliary warp-
threads by which the cut and uncut trams
are formed, are withdrawn. Fig. 3, is a top-
35 view of the trimming, after steaming the same.
Fig. 4, is a representation of the pattern-chart
according to which the tram-weft threads are
interwoven with the warp-threads of the head-
ing. Fig. 4^a, is a diagram showing the ar-
40 rangements of the warp-threads of the head-
ing and the interweaving of the tram weft-
threads with the same and with the auxiliary
warp-threads and the wires for forming the
looped trams. Fig. 4^b, is a diagram showing
45 the heading on a larger scale and the inter-
weaving of the tram weft-threads with the
warp-threads of the heading, and Figs. 5, 6
and 7 are respectively vertical transverse sec-
tions on lines 5 5, Fig. 1, 6 6, Fig. 2, and 7 7,
50 Fig. 3, said sections representing the differ-
ent steps in the manufacture of the trimming.

Similar letters of reference indicate corre-
sponding parts.

Referring to the drawings, A represents a
trimming which is composed of a heading a
55 and a facing b, the facing being formed of
silk, mohair or other trams which are partly
cut and partly uncut or looped, as shown
clearly in Fig. 3. The weft-thread is inter-
woven with the warp-threads of the heading 60
a and with a series of auxiliary warp-threads
d d, which is arranged at each side of the
heading.

The trimming is made on a loom of the or-
dinary construction by means of a single shut-
tle only, which passes the weft-thread through
the warp-threads and around the wires e at
each side of the heading which serve for form-
ing the looped trams. The warp-threads of
the heading are each formed of multiples of 70
threads, the end warp-threads being formed
of eighteen threads and the intermediate
warp-threads of two, four and six threads re-
spectively as shown clearly in Fig. 4^b. The
weft-thread is interwoven with the warp-
75 threads of the heading and with the auxiliary
warp-threads and with the wires e as shown
by the diagram in Fig. 4^a, the intermeshing
of the weft-threads with the warp-threads of
the heading being more clearly indicated in 80
Fig. 4^b, while the pattern-chart shown in Fig.
4, illustrates the eight successive picks by
which the facing and the selvage of the head-
ing is formed. The first and second pick at
the right hand side and the eighth and ninth 85
picks at the left hand side form a selvage at
each side of the heading while the interme-
diate picks form with the auxiliary warp-
threads d d and the wires e the trams from
which the facing of the trimming is produced. 90
When the trimming leaves the loom, it has
the appearance shown in Fig. 5, the trams of
the weft-thread being retained by the auxil-
iary warp-threads d d. The edges of the trams
are then cut off along the outermost warp- 95
threads d and the wires withdrawn from the
looped trams of the heading. The looped or
uncut trams d' d' are retained in the facing
and impart a certain design to the facing of
the trimming when the same is finished. The 100
tram weft-threads intermesh alternately with
the auxiliary warp-threads which are after-

ward removed and with the wires *e*. The wires *e* simply serve for forming the looped trams which are slipped off from the wires as the trimming is produced in the loom in the manner 5 well known to practical weavers. After the trimming is woven in the loom, it is removed and cut off at the edges so as to cut ends of some of the trams, while the trams which are looped in the wires remain in uncut or looped 10 condition. The auxiliary warp-threads by which the ends of the uncut trams are formed, are then removed in lateral direction, which can easily be done as they freely leave the cut trams. The facing of the trimming is 15 parted along the center-line of the heading and is then subjected to a steaming action by which the uniform rounded-off form of the facing shown in Fig. 7 is obtained in the manner well known to manufacturers of plush and 20 similar trimmings. By means of different pattern-charts different designs of looped or uncut trams may be produced in the cut trams, so that a variety of ornamental designs is

obtained by which a very characteristic and highly ornamental appearance is imparted to 25 the trimming, as the appearance of the looped or uncut trams differs essentially from the cut trams even though the color of the frame is alike.

Having thus described my invention, I 30 claim as new and desire to secure by Letters Patent—

A trimming composed of a heading formed of warp-threads and of tram weft-threads which are interwoven therewith so as to form 35 a selvage at each side of the heading, and a facing which is composed of cut and looped or uncut trams, substantially as set forth.

In testimony that I claim the foregoing as my invention I have signed my name in presence of two subscribing witnesses.

FRIEDRICH HASSENPLUG.
